UNITED STATES PATENT OFFICE.

PAUL BIENVAUX, OF PARIS, FRANCE.

TELEGRAPHIC-CODE APPARATUS.

1,276,616.

Specification of Letters Patent. Patented Aug. 20, 1918.

Application filed June 8, 1914. Serial No. 843,900.

To all whom it may concern:

Be it known that I, PAUL BIENVAUX, a citizen of the French Republic, residing at Paris, in the Republic of France, have invented certain new and useful Improvements in a Telegraphic-Code Apparatus, of which the following is a specification.

The apparatus essentially consists of a rectangular board divided into longitudinal 10 columns and horizontal cross-rows composed of squares provided with numerals. Movable bands are arranged at the side of this board in housings which comprise groups of vowels, of consonants and numerals (0 to 9) 15 the positions of the movable bands being determined by the key agreed upon.

If the apparatus is properly set, to each group of figures of the board there will correspond one consonant and one vowel forming a syllable composed of two characters; on the other hand, to each of the numerals 0 to 9, there will correspond one or two consonants so that the numbers can be transformed into pronounceable words composed 25 of five characters.

Referring to the accompanying drawings, illustrating the improved telegraphic code apparatus by way of example;

Figure 1 is a diagrammatic illustration 30 of the apparatus.

Fig. 2 is a sectional view of one form of construction of movable band, and Figs. 3 and 3^a are respectively a plan view and a cross-section of another form of construction of movable band.

Fig. 4 shows another manner of utilizing the apparatus, and

Fig. 5 and 5^a show respectively a sectional plan view and a cross-section of the mode 40 of mounting of the movable bands.

The apparatus illustrated in Fig. 1 permits the transformation of five figures (or of six figures between 100,000 and 113,999) into a word of five characters, and it essentially 45 consists of a rectangular board 1 divided into squares 2 arranged in six longitudinal columns and nineteen horizontal cross-rows. The figures 00, 01, 02, etc. . . up to 113 are marked in these squares in any convenient manner. The six columns correspond 50 to the six vowels A, E, I, O, U, Y and the nineteen cross-rows to nineteen consonants, the character Q not being used, as it does not form together with a vowel a syllable 55 which can be pronounced. If groups of five figures only have to be transformed into

words of five characters, it would be sufficient to mark only the figures 00, 01, etc. . . up to 99 and seventeen columns would be sufficient. The figures from 00, up to 113 60 are arranged in such a manner that they can be rapidly found.

Two housings 3 and 4, are arranged at the upper and lower end of the board 1 respectively, the length of the housings corresponding to three squares, and the upper housing 3 being arranged at the right hand side of the board, and the lower housing 4 at the left hand side thereof. Groups of three different vowels, for example A, E, I 70 and O, U, Y are marked in the housings 3 and 4 respectively, and these vowels are arranged to be moved in such a manner that although they remain in the same order, either vowel may be the first one. 75

Two housings 5 and 7, are provided at the right and at the left of the board 1, respectively being arranged at the upper part and the other at the lower part of the board, and the length of each housing being equal to 80 that of nine squares of the board. In each of said housings is arranged a band provided with nine different consonants, for example B, C, D, F, G, K, J, L, M for the housing 5, and N, P, R, S, T, V, W, X, Z 85 for the housing 7, no same consonant being used in both housings. The bands are made movable so that any of the consonants marked on the same may come to lie at the top. 90

The bands in the housings 5 and 7, and similarly the bands in the housings 3 and 4 may be interchanged. The nineteenth consonant H is marked in the housing 9 as well as in the housing 10, at the right and left of 95 the middle cross-row, being by itself a band with only one character. At the side of each of the housings 5 and 7, are arranged similar housings 6 and 8 respectively, the bands of which are marked with the figures 1, 2, 3, 4, 5, 1, 2, 3, 4, in the housing 6, and 6, 7, 8, 9, 0, 6, 7, 8, 9 in the housing 8. These bands are movable and interchangeable, similarly to the bands in the housings 5 and 7. 100

To each group of figures on the board 1 corresponds one vowel and one consonant. For example to number 93 correspond R and Y. To each one of the single numerals on the bands in the housings 6 and 8, there 110 corresponds generally two consonants; for example, according to Fig. 1, the two letters

D and L correspond to the numeral 3. For coding that consonant is chosen which sounds best in the word to cable.

As all the characters and numerals can be permuted $3 \times 3 \times 2 \times 5 \times 5 \times 2 \times 9 \times 9 \times 2 = 145,800$ different combinations can be made.

Fig. 2 shows on a larger scale and in section a form of movable band placed in the housing. This band consists of an endless strip 12, the length of which corresponds to about twelve or thirteen squares of the board. For the housing 4 the vowels O, U, Y, O, U and further the vowels A, E, I, A, E are printed on this band successively, the two groups of vowels being separated by a blank space 11. The band 12 is guided over rollers 13, 14, one of which can be rotated by means of its axle which is adapted to be fixed in position by a clamping-screw.

Fig. 3 shows a different construction of the housings and of the movable bands. A slide 16 on which the vowels O, U, Y, O, U, are marked is provided with a rack 17 and is guided in a groove 15 of the housing, being operated by a toothed wheel 18, which engages with the said rack and the axle 19 of which is provided with a small hand wheel 20 and with a clamping-screw 21. When the hand wheel 20 is turned, the slide 16 is moved and the vowels are brought in their proper positions in the housing, according to the key, which has been chosen. The vowels A, E, I, A, E are marked on the back of the slide so that the two groups of vowels may be interchanged by simply turning the slide upside down.

The apparatus is used as follows:

The key is composed by designating the numeral or character of each band which has to occupy a determined position in the housing, for example the division (a—b—c—d—e—f) of the bands. The key in the combination shown in Fig. 1 would be 1, 9, B, A, Z, Y. With another combination the characters and numerals of the bands have to be moved so that the characters and numerals chosen appear in the squares agreed upon (a—b—c—d—e—f), 145,800 combinations being possible.

Let us suppose that the phrase to be cabled and coded be represented by the numbers 25,342, 02435, 75,206, 10,025.

These groups of figures must always be composed of five figures at least, and if a group should not have the sufficient number of figures, as many zeros are added at the left as are required. The groups of figures may even comprise six figures.

Each group is divided into three sub-groups, the group at the right hand end having one figure, the second group two figures, and the third group two or three figures, according to whether the number lies between 00000 and 99999 or between 100,000 and 113,999. With the key shown in Fig. 1,

the first number would be decoded as follows 25=WY, 34=LY, 2=J or C.

Of the two characters J or C, that character is chosen which gives the best consonance.

The cablegram given by way of example will therefore be decoded either into WYLYC, DUWUG, RADON, CODUG, or WYLYJ, DUWUG, RADOV, CODUG.

If another key was used, the characters 75 would not in the least be similar to the groups of characters obtained by the key used in Fig. 1.

The characters on the movable bands could be arranged in any convenient manner, the arrangements described and shown being given only by way of example.

Instead of printing the vowels, and similarly the single numerals, on two different bands and the consonants on three different bands, one of the latter bands comprising only one character, all the vowels, and similarly all the consonants and numerals, could respectively be printed on one single band whereby the number of combinations obtained would of course be reduced. On the other hand the characters and single numerals could be printed on a greater number of bands, whereby the number of possible combinations would be increased.

The apparatus hereinbefore described may also be used for transforming groups of six figures into words of five characters.

Referring to Fig. 4, the six columns of the board 1 are designated by special signs for example $\alpha, \beta, \gamma, \delta, \epsilon, \omega$, four of said columns, for example, those designated by $\alpha, \beta, \gamma, \delta$, comprising only numbers below one hundred (100), and the whole group of numbers being arranged in the natural order. 105 In the first four columns are marked $19 \times 4 = 76$ numbers, that is to say the numbers from 00 to 75. The remaining numbers lower than 100, that is to say from 76 to 99, which are marked in the two last columns 110 of the board 1, are marked again on a special board 11, which is arranged either at the bottom or at the top of the main-board 1, and which is divided into six columns registering with the six columns of the main-board 1. To each column corresponds one of the six vowels A, E, I, O, U, Y.

The special board 11 has four cross-rows which are designated by $\alpha, \beta, \gamma, \delta$, viz., by the same signs as the first four columns of 120 the main-board 1 which contain the numbers lower than 100.

Let us suppose for example, that the number 570,130 is to be transformed into a word of five characters. The number is divided 125 into three groups of two figures, and the groups 57 and 01 are transformed into syllables of two letters by means of the main-board 1. To the right hand group 30 will correspond two letters but only one 130

single letter is used which is determined as follows. The number 30 on the main-board is in the column designated ϵ and its cross-row registers the consonant P, while its 5 column registers the vowel U. Which one of the two letters is to be used is determined by a pre-arrangement as to the sequence of the use of the vowel and consonant in the various divisions with respect to the columns 10 or cross-rows marked α , ϵ , γ , δ , in which the third division is to be found on the main-board or on the special board respectively. The following table gives an example of such pre-arrangement.

15	To the signs hereunder indicating the column of the main-board or the cross-row of the small-board where the third division is to be found,	Will correspond the following combinations for the syllables representing the two first divisions.	
		1st division.	2nd division.
20	α	Vowel, consonant.	Consonant, vowel.
	ϵ	Consonant, vowel.	Consonant, vowel.
	γ	Consonant, vowel.	Vowel, consonant.
	δ	Vowel, consonant.	Vowel, consonant.

25 It is evident that any others of the analogous twenty-four combinations corresponding to the permutations of the signs α , ϵ , γ , δ , may be adopted.

30 Therefore, the two characters corresponding to 57 being A and B, and those corresponding to 01 being O and C, on the main-board 1, as 30 stands in the column ϵ , the number 570,130 is translated as follows:

35 57=B A (consonant and vowel),
01=C O (consonant and vowel), and
30=P.

570,130=BACOP.

For the number 508,694, the division 94 in 40 the small board 11 corresponds to the vowel O and stands in the cross-row δ , so that the translation of the number is:

508694=YRENO.

45 By inverting the method, words of five characters are easily transformed into numbers of six figures.

50 Of course, the apparatus may be arranged in such a manner that different arrangements can be used for the main board and the small board, as the movable bands for

characters and numerals may be replaced by other bands printed differently.

Fig. 5 illustrates the manner in which said bands are mounted so that they can easily be removed. The band—(x) rests in 55 a sheath, (y) which is adapted to be moved in a guide-piece and to be fixed in the desired position by means of a clamping-screw (u).

What I claim is:

1. In a code apparatus a base having on one board spaced groups of numerals comprising at least two digits to each group arranged in longitudinal columns and horizontal cross-rows; alphabetical characters on movable bands arranged so that each column has a vowel at either its top or foot and each cross-row a consonant at either its right or left hand end; each cross-row having also, one of the ten digits at the same end as its consonant. 60

2. In a code apparatus a base having on one main-board spaced groups of numerals comprising at least two digits to each group arranged in six longitudinal columns and nineteen horizontal cross-rows, the said six columns being marked with distinct signs, four of said columns containing only numbers lower than 100; alphabetical characters on movable bands arranged so that each column has a vowel at either its top or foot, and each cross-row a consonant and one of the ten digits at either its right or left hand end; either at the bottom or at the top of said main-board a small board comprising six longitudinal columns and four horizontal cross-rows, said horizontal cross-rows being marked with the same signs as four of the columns of the main-board, the numbers lower than 100 which are not 70 marked in said four columns of the main board being marked in the squares of the small board, substantially as described and shown and for the purpose set forth. 80

3. In witness whereof I have hereunto set my 85 hand in the presence of two witnesses.

PAUL BIENVAUX.

Witnesses:
